(57) **CLAIM**

The ornamental design for an object for the control of a remote controlled toy through attitudinal orientation of the object, as shown and described.

DESCRIPTION

FIG. 1 is a plan view of an object for the control of a remote controlled toy through attitudinal orientation of the object. FIG. 2 is a right side view of the object for the control of a remote controlled toy through attitudinal orientation of the object of FIG. 1, the other side view being a mirror image of the side view of FIG. 2.

FIG. 3 is a top view of the object for the control of a remote controlled toy through attitudinal orientation of the object of FIG. 1; and,

FIG. 4 is a bottom view of the object for the control of a remote controlled toy through attitudinal orientation of the object of FIG. 1.

The bottom of the object for the control of a remote controlled toy through attitudinal orientation of the object does not form any part of the design.

The broken lines shown in FIGS. 1-4 are for illustrative purposes only and form no part of the claimed design.
